MUSIC BOX

Norman T. Boyle, Brooklyn, N. Y.

Application August 16, 1946, Serial No. 691,075

2 Claims. (Cl. 84—102)

1.

This invention relates to improvements in music boxes.

The principal object of this invention is the provision of a music box incorporating a xylophone construction. And a further object of the invention is the provision of a music box of this type in which a plurality of tunes may be played by the simple expedient of shifting some of the parts thereof relative to the other parts.

Another object of this invention is the provision of a xylophone which may be actuated by the turning of a crank handle and which automatically plays a predetermined tune and more particularly a selected tune chosen from a plurality of predetermined tunes.

A preferred embodiment of this invention is shown in the accompanying drawing in which—

Fig. 1 is a vertical section through a music box incorporating the features of the present invention, said section being taken on the line 1—1 of Fig. 2;

Fig. 2 is a section taken at right angles to the section shown in Fig. 1, and being indicated by the line 2—2 in Fig. 1; and

Fig. 3 is a perspective view of said music box showing a supporting strap attached thereto.

The music box forming the subject matter of this application includes a casing 10 in which the mechanism hereinafter described is used, and a supporting strap 11 affixed at its ends to said casing whereby the music box may be suspended from around the back of the neck while played. A shaft 13 extends through the casing 10 and mounted on said shaft and keyed thereto is a plurality of drums 15. Also keyed to said shaft is a gear wheel 17 which meshes with a smaller gear wheel 18, which latter gear wheel is in turn connected to a larger gear wheel 19. A crank handle 20 is mounted on the outside of the casing 10 and is connected through a hole therein to a smaller gear wheel 22. This latter gear wheel 22 engages the larger gear wheel 19 above mentioned and when, therefore, the crank handle 20 is worked in the usual manner, the several gear wheels above described, rotate at differing rates of speed, and since the last of the gear wheels 17 is keyed to shaft 13, said shaft is also caused to rotate. By the same token, the drums 15 which are fixedly mounted on the shaft 13, engage in rotary movement when the crank handle is turned.

It will be noted in Figs. 1 and 2 that on the peripheral surface of each of these drums 15 is a plurality of small projections 30. Closer examination of Fig. 1 will reveal that these projections

2.

are arranged along four circumferential lines. That is each drum is provided with four series of projections 30, each of said series lying on a circumferential line, all of said series being spaced from and parallel to each other. The projections of each series are spaced from each other at predetermined intervals which may or may not be, and usually are not, uniform.

Slidably mounted in the casing 10 on a line 16, which is parallel in respect to the shaft 13 above mentioned, is a shifting or sliding bar 32. This bar extends outwardly from the casing at both ends thereof as shown in Fig. 2. It will be noted that a plurality of hammers 35 are mounted on said shifting bar 32 by means of spring members 36. It will also be noted that affixed to each of said spring members 36 is a small lug 37. Reference to Fig. 2 will show that the lugs 37 are positioned to encounter the projections 30 when the drums 15 are caused to rotate. As said projections strike said lugs, the hammers 35 are raised from their normal positions of rest, and as these projections disengage said lugs, the hammers are enabled to return to their said normal positions of rest. Since these hammers are mounted on spring members, the return movement last above referred to is sharp and pronounced.

A xylophone 40 is mounted on the inside of the casing 10 as shown in Figs. 1 and 2. It will be noted that the hammers 35 are positioned to strike the vibrating members 41 of the xylophone. Thus it is that when the crank handle 20 is operated and the drums 15 caused to rotate, a staccato movement of the hammers 35 is effected through the tripping engagement of the projections 30 with the lugs 37. The timing of said movement of the hammers is determined by the spacing of the projections 30.

It will be recalled that each drum 15 is provided with four circumferential series of projections 30. It will further be recalled that the hammer supports 36 are mounted on a shifting bar 32. The lugs 37 on said hammer supports are wide enough for engagement with a single series of projections 30, but they are not sufficiently wide to engage two series of projections at the same time. Hence when the shifting bar 32 is moved its longitudinal axis in either direction, thereby carrying with it the several hammer supports 36, it is possible to set the lugs 37 for engagement with a selected series of projections 30, that is with any one of the four series above referred to.

These projections 30 perform the same function as the projections in an ordinary Swiss mu-

sic box. Each series of projections on each of the drums 15 taken in conjunction with the corresponding series on each of the other drums, provides for the playing of a particular tune. To change the tune one simply shifts the shifting bar 32 one or more notches as designated by the character reference 50 in Fig. 1. There are four notches on the shifting bar, each corresponding to a series of projections 30 on the drums 15. At the bottom an opening 51 is provided through which the musical sounds are adapted to pass.

It will be understood that the foregoing is a description of a preferred embodiment of the invention and that said embodiment may be changed in many ways within the spirit of the invention.

I claim:

1. In a music box including a xylophone, a shifting bar, said bar mounted longitudinally of the xylophone, a plurality of spring members affixed to said bar, a plurality of hammers mounted at the free ends of said spring members to selectively engage said xylophone, a lug on each of said spring members, a plurality of drums, a plurality of tripping members circumferentially disposed on each of said drums to selectively engage and trip the lugs causing the hammers to strike the xylophone, said tripping members being arranged in a series of concentric groups on each drum, means to cause simultaneous rotary movement of said drums to bring a group of tripping members into engagement with said lugs and means for operating said

shifting bar to cause engagement of said lugs with any other group of tripping members.

2. In a music box including a xylophone, a slidably operable shifting bar, said bar mounted longitudinally of the xylophone, a plurality of spring members having one end affixed to said bar, a plurality of hammers mounted on the opposite ends of said spring members to engage said xylophone, a lug on each of said spring members positioned intermediate their ends, a plurality of drums, a plurality of tripping members circumferentially disposed on each of said drums to selectively engage and trip the lugs, thereby actuating the hammers, said tripping members being arranged in a series of concentric groups on each drum, means to cause simultaneous rotary movement of said drums to bring a group of tripping members into engagement with said lugs and slidable movement of said shifting bar causing engagement of said lugs with any other selected group of tripping members.

NORMAN T. BOYLE.
